WASHBOARD

Application filed March 13, 1928. Serial No. 261,299.

This invention relates to improvements in washboards and has as one of its objects to provide a washboard having a rubbing surface of novel formation and designed to materially increase the efficiency of the board in 5 cleansing the clothes rubbed over the surface thereof.

The use of washboards embodying corrugated sheet metal rubbing surfaces is old and 10 well known, and while the corrugated surfaces of such boards facilitate the cleansing of the clothes rubbed over the surface, nevertheless the corrugations become corroded and soon worn away so that such a board becomes 15 unfit for further use. Therefore the invention has as a further object to provide a washboard the rubbing surface of which will consist of a board proper, of wood, and strands of wire extending transversely of the surface 20 of the board and serving the same purpose as the corrugations of a sheet metal board, the invention contemplating so anchoring the ends of the wire strands that, in the event of damage to any of the strands or a corroding 25 or wearing away of any of the strands, the ones which have become unfit for use may be readily replaced.

Another object of the invention is to so mount the wire strands upon the face of the 30 board that there will be no likelihood of upward or downward displacement of the strands such as might, except for the means provided by the invention, take place.

Another object of the invention is to provide 35 a novel means for mounting the soap ledges of the board between the legs of the board and upon the opposite faces of the board proper, so as to insure against loosening or displacement of these parts of the 40 board.

Another object of the invention is to provide, in combination with a wash board, novel means whereby the same may be securely anchored to the rim of a washtub so as to 45 prevent slipping or displacement of the board while the same is in use thus obviating the necessity of the user of the board manually holding the same against such displacement.

While the accompanying drawings and the 50 description which is to follow, constitute a

disclosure of the preferred embodiment of the invention, it will be understood that various changes may be made within the scope of what is claimed.

In the accompanying drawing:

Figure 1 is a view in front elevation of the washboard embodying the invention;

Figure 2 is a side elevation thereof;

Figure 3 is a vertical sectional view taken centrally through the board substantially on the line 3—3 of Figure 1 looking in the direction indicated by the arrows;

Figure 4 is a horizontal sectional view through the board taken substantially on the line 4—4 of Figure 1 looking in the direction indicated by the arrows;

Figure 5 is a horizontal sectional view through the board taken substantially on the line 5—5 of Figure 1 looking in the direction indicated by the arrows;

Figure 6 is a fragmentary view in side elevation of a portion of the board, the adjacent leg being removed in order to illustrate more clearly the manner in which the wires are mounted upon the opposite faces of the board.

Generally speaking the washboard embodying the invention, includes, in its construction, the board proper which is indicated in general by the numeral 1 and the legs which are indicated in general by the numeral 2 and, in accordance with the principles of the invention, the vertical edges of the board 1 are disposed within vertical grooves 3 formed in the inner faces of the said legs 2, the grooves in the legs extending downwardly in the inner sides of the legs from the upper ends thereof to a point spaced above the lower ends of said legs and the grooves being slightly less in length than the height of the board 1 so that the lower corners of the board rest in the lower ends of the grooves, and the upper edge of the board projects slightly above the upper ends of the legs. The numeral 4 indicates the cap piece of the board which does not differ materially from the cap piece of the ordinary wash board except that it is provided in its under side with a longitudinal groove 5 in which the projecting upper edge of the board 1 is accommodated. The legs 2 are secured to the vertical edges of the board

1 through the medium of screws or other fastening elements 6 which are of a character to permit of removal of the said legs 2 from the board, under conditions to be presently explained, the cap piece 4 being likewise secured in any suitable manner in place upon the upper ends of the legs 2 and the upper edge of the board 1.

The soap ledges of the board are indicated by the numeral 7 and these ledges are arranged one at each face of the board 1 in position suitably spaced below the cap piece 4 so that bars of soap of ordinary size may be disposed upon the ledges and against the respective faces of the board 1 and supported upon said ledges when not in actual use. Preferably the board 1 is formed in its opposite faces with transversely extending grooves 8 in which the inner edges of the soap ledges 7 are disposed, each leg 2 being formed in the side walls of its groove 3 with notches 9 and the ends of the ledges 7 being notched as at 10 to provide rabbets 11 which project into the notches 9, the soap ledges being in this manner securely anchored with respect to the legs 2 and the board 1 and held against any displacement.

In order that each face of the board 1 may constitute a roughened rubbing surface, a plurality of rods 11 are disposed against each face of the board, the rods which are arranged against one face of the board being of greater diameter than the rods which are arranged against the other face of the board. The rods of each series are arranged to extend horizontally in equi-distantly spaced relation with respect to each other and each series of rods extends substantially throughout the entire height of the face of the board 1 against which they are disposed, between the lower edge of the board and the respective soap ledge 7. Each rod 11 is formed throughout its length with a series of oppositely directed gradual bends or undulations indicated by the numeral 12, and in order that the rods may assume a position close to the respective face of the board 1, the board is formed in each of its faces with a plurality of horizontally arranged rows of longitudinally and transversely concave recesses or grooves which are indicated by the numeral 13 and which are of a contour to snugly accommodate the inwardly directed bends or undulations of the rods, as clearly shown in Figure 5 of the drawing. In order that the rods 11 may be securely anchored in place upon the faces of the board 1, the board is formed in its vertical edges at each end of each of the series of recesses 13, with notches 14, and the groove 3 of each leg is formed in its side walls at the corresponding intervals, with notches 15, and as illustrated in Figures 5 and 6 of the drawing, the ends of the rods are turned inwardly at right angles as at 16 so as to engage in the notches 14, with their bends

seating in the notches 16, and, as the legs are secured to the vertical edges of the board by screws 6 and the notches are of dimensions to snugly accommodate these ends of the rods, the said ends of the rods will be securely clamped in place and there can be no displacement of the rods. It will be understood at this point that due to this clamping of the ends of the rods and the seating of the inwardly presented bends in the recesses 13, 75 upward or downward springing or displacement of any of the rods is prevented.

From the foregoing description and an inspection of the drawing it will be evident that the arrangement of the rods 11 with respect to the faces of the board 1 produces a highly efficient rubbing surface and permits clothing, rubbed over the surfaces of the board, to be more readily cleansed than is ordinarily possible in the use of wash boards of the ordinary construction. It will also be evident that due to the fact that the rods 11 at one side of the board are of greater diameter than the rods at the other side, one side of the board, namely that side at which the rods of larger diameter are located, may be employed to best advantage in the washing of heavy articles of clothing, whereas clothing of finer material may be more effectually cleansed by rubbing it over the other face of the board 95 at which the rods of smaller diameter are arranged.

In order that the wash board may be held stationary with respect to the tub in which it is disposed, hooks 17 are pivotally mounted 100 at one end as at 18 one upon each of the legs 2 at the outer side thereof and near the upper end of the leg, and these hooks are provided each with a pair of bills indicated by the numeral 19 so that the hooks may be 105 swung to extend from one side or the other of the board, depending upon which face of the board is being used as the rubbing face, and corresponding bills of the hooks engage over the upper edge of the washtub.

It will be evident that, in the event any of the rods become damaged and requires replacement, the removable fastening elements for the legs of the board may be removed and the right angularly bent ends of the rod disengaged from the notches in the vertical edges of the board 1 and the rod thus bodily separated from the board, whereupon a new rod may be substituted therefor.

Having thus described the invention, what we claim is:

1. A wash board comprising a board proper, and a plurality of rods extending transversely of the surface of the board, the rods having alternately inwardly and outwardly presented bends therein curved longitudinally, the face of the board being formed with a plurality of series of transversely extending spaced concave recesses therein spaced from each other at their ends and ac-

commodating the inwardly presented bends of the rods with the rods continuously in contact with the board but projecting outwardly therefrom for the entire width of the board.

5 2. A wash board comprising a board proper, the face of the board being formed with a plurality of transversely extending series of longitudinally spaced concave recesses, and a plurality of rods extending transversely of the said surface of the board and having alternately inwardly and outwardly presented bends therein, the inwardly presented bends of the rods being accommodated within the said recesses to prevent transverse movement of the rods longitudinally of the board and the said recesses being of a depth less than the circumference of the rods at their said bends whereby the rods 10 project from the board for the full width thereof, the rods being in continuous contact with the surface of the boards throughout their lengths.
